Primary Examiner — Wan Laymon

Assistant Examiner — Mark Booker

(74) *Attorney, Agent, or Firm* — Banner & Witcoff, Ltd.

(57) **CLAIM**

The ornamental design for a garment, as shown and described.

DESCRIPTION

FIG. 1 is a left perspective front view of a garment showing my new design in an in-use configuration;

FIG. 2 is a right perspective view thereof;

FIG. 3 is front view thereof;

FIG. 4 is a rear view thereof;

FIG. 5 is a left side view thereof;

FIG. 6 is a right side view thereof; and,

FIG. 7 is an enlarged view of FIG. 3 showing the claimed area in isolation from the environment.

The broken lines immediately adjacent to the shaded areas represent unclaimed boundaries of the design. The broken lines showing the remainder of the garment represent unclaimed subject matter and form no part of the claimed design.

1 Claim, 7 Drawing Sheets
